1

Our invention relates, generally, to current collectors, and it has reference, in particular, to pantograph current collectors for electrically operated vehicles.

Tests which have been made on pantograph current collectors of the usual type show that the stress in the trolley conductor is greatly affected by the type of pantograph shoe mounting which is used. A mounting which has no flexibility near the point of support of the shoe produces very high stresses in the conductor, particularly when the vehicle is operating at relatively high speeds. Similarly, a flexible mounting which binds due to friction or operates so as to engage a rigid stop is not very effective in reducing the conductor stress.

The double shoe mounting, now in common use, uses pivoted shoe levers inclined to the front and rear, and held up by springs for supporting the two shoes. The shoes are attached to the outer ends of the levers by pivoted connections and can thus rotate freely about the pins. With this type of mounting, aerodynamic lift, aerodynamic drag and wire friction all combine to rotate the support levers of the leading pantograph shoe so as to force the leading shoe upwardly against the conductor. Conversely, these forces act to rotate the support levers of the trailing shoe and force the trailing shoe away from the conductor. At high speeds, this action is so great that the leading shoe is often lifted to the limit of its upward travel and rides against a solid stop, thus losing all the benefits of spring mounting. The trailing shoe is forced away from the conductor and often leaves it entirely.

Since the pivot connection between the shoe and shoe levers is in the usual shoe mounting positioned below the conductor, the shoe has a center of rotation below the contact surface of the conductor. Thus wire friction tends to rotate the shoe so that only the leading edge of the shoe is in contact with the conductor thus increasing the angle of attack, so that the aerodynamic lift becomes relatively large. In addition, with a center of rotation below the conductor, an increase in friction rotates the shoe to a position where the frictional force is still greater, thus producing a "stubbing" action, wherein the leading edge of the shoe tends to dig into the conductor. In addition, when the center of rotation of the shoe is below the conductor, and an aerodynamic flutter of the shoe commences, the frictional force appears to feed energy into the resulting oscillation, so that the flutter increases. Furthermore, the mounting

2

system usually used with pantograph shoes contains a plurality of pivot points each having a relatively large amount of friction which tends to bind the pivot action and nullify the action of the springs.

Generally stated, it is an object of our invention to provide a current collector which is simple and inexpensive to manufacture, and which is efficient and reliable in operation.

10 More specifically, it is an object of our invention to provide for resiliently mounting a pantograph shoe so that the center of rotation of the shoe is above the contact surface with the trolley conductor.

15 It is also an object of our invention to provide for reducing the tendency of a pantograph shoe to tilt so that the leading edge produces a "stubbing" action with the conductor.

20 Another object of our invention is to provide a resilient parallel motion support for a pantograph shoe.

25 Yet another object of our invention is to provide for mounting a pantograph shoe on an elastic pivot structure.

25 Still another object of our invention is to provide for resiliently mounting a pantograph shoe for limited resilient rotational movement on a vertically resilient support.

30 It is an important object of our invention to provide for reducing the operating friction of pantograph shoe mountings.

35 A further object of our invention is to provide a current collector wherein the conductor friction and aerodynamic lift do not tend to rotate the collector support and force the collector upwardly against the conductor.

40 Another important object of our invention is to provide a current collector which is relatively stable over a wide range of operating speeds.

40 Other objects will, in part, be obvious and will, in part, be explained hereinafter.

In accordance with one embodiment of our invention, a pantograph shoe mounting is provided having spaced support members with relatively flat spring supports extending to the front and rear on the top and the bottom. The projecting ends of the spring supports are connected to provide a vertically movable resilient parallel motion support. Elastic pivots are provided adjacent the ends of the supports at both the front and rear ends for so supporting a pair of main pantograph shoes as to provide centers of rotation above the contact surfaces of the shoes. An auxiliary shoe is rigidly connected to the support

members intermediate the main shoes and below the normal operating level thereof.

For a more complete understanding of the nature and scope of our invention, reference may be made to the following detailed description which may be read in connection with the accompanying drawings, in which:

Figure 1 is an end elevational view, partly in section, of a pantograph current collector of the usual type;

Fig. 2 is an end elevational view, partly in section, of a pantograph current collector showing, in side elevation, a mounting embodying the invention in one of its forms;

Fig. 3 is a partial end elevational view, partly in section, of a pantograph current collector showing a mounting embodying the invention in another of its forms;

Fig. 4 is an enlarged longitudinal cross-sectional view of a well known type of elastic shear bushing used in connection with the current collector mounting shown in Fig. 3;

Fig. 5 is a plan view of a pantograph collector showing a mounting embodying the invention in another of its forms;

Fig. 6 is an enlarged partial plan view of a current collector showing the pantograph shoe mounting used on the current collector shown in Fig. 5;

Fig. 7 is an enlarged partial side elevational view of the mounting shown in Fig. 6;

Fig. 8 is an enlarged partial end elevational view of the mounting shown in Figs. 6 and 7;

Fig. 9 is a partial side elevational view of a modification of the mounting shown in Figs. 6 and 7 illustrating a method of mounting the elastic pivot by means of an elastic shear connection;

Fig. 10 is a plan view of the elastic pivot shown in Fig. 9, with parts removed to show details of the elastic shear connection;

Fig. 11 is an enlarged plan view of the elastic shear connection used in the mounting of Figs. 9 and 10;

Fig. 12 is an enlarged end elevational view of the elastic shear connection; and

Fig. 13 is an enlarged plan view of the lower member of the elastic pivot shown in Figs. 9 and 10.

Referring to Fig. 1, the reference numeral 10 may denote, generally, a mounting for a pair of pantograph shoes 11 which are disposed to engage a trolley conductor 12. The mounting, which is typical of the type commonly used, comprises inclined front and rear arms 13 pivotally connected to a support member 14 which is mounted on a pantograph support structure 15 and pivotally connected to the leading and trailing shoes, respectively, by pins 16.

It will be observed from examination of this construction that since the pins 16 are necessarily below the trolley conductor 12, the frictional force between the leading shoe (which may, for example, be on the left-hand side of the figure) and the trolley conductor, produces a moment tending to rotate the shoe in a clockwise direction. This forces the leading edge of the shoe upwardly against the conductor which increases the frictional force and tends to still further rotate the shoe.

Upon further examination of this type of construction, it will be observed that the frictional force acting on the leading shoe, together with aerodynamic drag, and the aerodynamic lift acting on this shoe, also tend to rotate the support lever 13 of the shoe in a clockwise direction so

as to lift the trolley conductor. At high speeds, this action is so great that the leading shoe 11 is often lifted to the limit of its upward travel. This not only causes the support lever to ride solidly against the stop 17, but it also produces relatively high stresses in the trolley conductor. At the same time, these forces acting on the support lever of the trailing shoe, tend to rotate it in a clockwise direction away from the conductor.

Referring to Fig. 2, the reference numeral 20 may denote, generally, an improved form of pantograph shoe mounting, wherein relatively flat spring supports 21 and 22 may be secured to the upper and lower sides of a support member 23, which may be mounted on the pantograph structure 15, in a manner similar to that usually used with the pantograph structures of the prior art. The spring supports 21 and 22 may be connected adjacent their ends by spacing members 25, so as to provide a resilient parallel motion structure 26 which is movable in the vertical direction only.

The pantograph shoes 11 may be mounted on the parallel motion structure 26 by means of elastic pivot supports 27, which may be disposed to provide an effective center of rotation of the shoes at points *a* above the surface of contact of the shoes 11 with the conductor 12. These elastic pivot supports 27 may, for example, each comprise a substantially rigid lower member 29, which may be rigidly connected to the spacing member 25, and a substantially rigid upper member 30 to which the pantograph shoe 11 may be rigidly connected by means of a pin 31. The upper member 30 of the elastic pivot support may be somewhat shorter than the lower member 29 and the two members may be connected by relatively flat springs 32 and 33 which are inclined inwardly and upwardly so as to provide a trapezoidal closed support structure with the spring members 32 and 33 having an effective point of intersection at the point *a* above the surface of the pantograph shoe 11.

With the current collector shown in Fig. 2, the pantograph shoes 11 are relatively free to move in a vertical direction under the action of the spring members 21 and 22. Since there are no sliding surfaces, the action of these spring members is substantially undamped, and the current collectors may thus move readily to follow irregularities in the trolley conductor 12.

Since the pantograph shoes 11 are mounted on elastic pivot supports 27, whenever any force such as frictional drag, aerodynamic drag or aerodynamic lift operate to retard motion of the shoe along the conductor 12 in a direction from right to left, for example, the elastic pivot supports function to produce rotation of the shoe in a counterclockwise direction. This reaction prevents "stubbing" between the pantograph shoe and the conductor, reduces aerodynamic lift because it reduces the angle of attack, and prevents lifting of the trolley conductor. In addition, since the elastic pivots are mounted on a parallel motion structure, none of these forces tend to produce a moment lifting the leading pantograph shoe against the conductor as was the case in the usual construction shown in Fig. 1, or lowering the trailing shoe.

Referring to Fig. 3, the reference numeral 35 may denote, generally, a modified form of pantograph shoe mounting, wherein a parallel motion structure 34 comprising rigid upper and lower links 36 and 37 connected to a support member 38 at one end and by a spacer 39 at the other end, is used to mount the pantograph shoe 11 on

a pantograph structure (not shown). The upper and lower links, support member and spacing member may be connected by means of elastic shear members 40 so as to provide for resilient vertical movement of the spacing member 39.

The elastic shear members 40 may be of any suitable construction comprising, for example, as shown in Fig. 4, a center pin or shaft 41 which may be firmly connected to the upper and lower link members by reason of a press fit, or the like, and a tubular sleeve 43 which may be firmly connected to the support member 38 or spacing member 39 in a like manner. The sleeve and shaft may be connected to each other by means of an interposed sleeve of natural or synthetic rubber which may be vulcanized thereto.

The pantograph shoe 11 may be mounted on the parallel motion structure 34 by means of an elastic pivot structure 47. This structure may comprise rigid lower and upper link members 48 and 49 connected by means of inwardly and upwardly inclined rigid link members 50 and 51 forming a closed force structure and having an effective point of intersection at a point *b* above the surface of contact of the shoe 11 with the conductor 12. The shoe 11 may be rigidly connected to the upper member 48 by means of a bolt 53, and the lower member 48 comprising a bar, may be connected to the spacing member 39 on one side thereof, in any suitable manner such as by means of welds 54, extending along adjoining surfaces of the members 48 and 39 where they overlap. The upper and lower members 48 and 49 and the connecting members 50 and 51 may be connected together by means of elastic shear members 40 of a type similar to that described in connection with the parallel motion structure 34, so as to provide an effective elastic pivot structure with a point of rotation above the contact surface of the current collector 11.

Referring to Fig. 5, the reference numeral 55 may denote, generally, a pantograph current collector having a pair of main pantograph shoes 11 positioned in substantially parallel spaced relation for engaging a current collector 12. The pantograph shoes 11 may be resiliently supported on a pantograph structure 15 by resilient mounting means 60 and provided with a rigidly mounted auxiliary shoe 61 intermediate the main shoes for preventing excessive deformation of the resilient mounting means.

Referring to Figs. 6, 7 and 8 it will be seen that the resilient mounting means 60 may comprise support members 62, which may be secured to the pantograph structure 15 by pins 63, which pass through openings in lugs 64 on the pantograph structure and are positioned in elongated openings 65 at each side of the support member. Attached to the upper side of the support member 62 are spring members 66 which may be fastened by means of a plate 67 and bolts 68 so as to extend to the front and rear of the support member. The spring members 66 may comprise relatively flat springs having elongated openings 69 therein adjacent each end so as to provide spaced spring arms 70 and 71. Additional spring members 72 may be secured to the support member 62 on the lower side so as to extend to the front and rear of the support member in substantially parallel spaced relation with the upper spring members 66. Spacing means may be provided adjacent the ends of the spring members 66 and 72 comprising, for example, a spacing block 74 to which the spring members may be secured by means of bolts 75 so as to provide a

resilient parallel motion structure which is movable in the vertical direction only.

The pantograph shoe 11, which is shown in outline, may be connected to the spring members by means of an elastic pivot structure designated generally by the numeral 77. The elastic pivot structure 77 may, for example, comprise a lower rigid bar 78, which may be connected to the spacing block 74 by means of bolts 79, and an upper rigid member 80 which may be rigidly connected to the shoe 11 by means of a lug 81 and a bolt 82. The upper rigid member 80 may be substantially shorter than the lower member 78. These upper and lower members may be operatively connected by means of flat spring members 83 and 84 which may be secured to the ends of the upper and lower members by means of screws 85. The relative lengths of the upper and lower members 78 and 80 may be so arranged that the spring members 83 and 84 are inclined inwardly and upwardly so that if extended, they would intersect at a point *c* which is the effective pivot point of the elastic pivot.

The spring members 83 and 84 are preferably relatively flexible so as to provide relatively free rotation of the shoe about the pivot point *c*. Vertically the pivot 77 acts as a rigid beam. The spring members 66 and 72 are relatively rigid. Vertically they act as an elastic parallel motion structure, while in the horizontal direction they act as a rigid beam. The spring members 83 and 84 may, for example, be of spring steel approximately 1 inch wide and .032 inch thick. The spring members 66 and 72 may be of spring steel $\frac{1}{16}$ inch thick and 3 to 4 inches wide. Thus, whenever frictional forces or aerodynamic drag act on the pantograph shoe, the shoe tends to rotate in a counterclockwise direction about the pivot point *c*. This tends to reduce the frictional drag or aerodynamic drag since it reduces the angle of attack, and thus restores the shoe to its normal operating position.

The length of the spring members 83 and 84 may be so selected that the upper rigid member 80 of the elastic pivot is only a relatively small predetermined distance above the upper spring member 66. Too great a deformation of the elastic spring members 83 and 84 by rotation of the shoe 11 is thus prevented since the rigid member 80 acts as a stop. Deformation of the upper and lower spring members 66 and 72, beyond a predetermined amount, is prevented by reason of the auxiliary pantograph shoe 61 which is positioned intermediate the main pantograph shoes, and which may be rigidly connected to the support member 62 by means of depending ears 87 and bolts 88.

Referring to Figs. 9 through 13, it will be seen that the shoe 11 may be connected to the upper member 86 of the elastic pivot structure 77 by means of screws 89. The structure 77 may be connected to the parallel motion structure by means of an elastic shear device 90, shown in Figs. 11 and 12. Resilient movement of the elastic pivot may thus be provided about an axis parallel to the trolley conductor, thus permitting horizontal misalignment of the pantograph shoe when one is in an operating position lower than the other without deforming the spring members 83 and 84. For example, the lower rigid member 92 of the elastic pivot may be provided with a recess 93 intermediate the ends for receiving the elastic shear device 90.

The elastic shear device 90 may comprise a substantially rectangular plate 94 having cylind-

cylindrical projections 95 at the opposite ends and provided with openings 96 for receiving bolts whereby the device may be connected to the lower end of the spacing member 74. Mounting blocks 97 may be positioned about the cylindrical projections 95 and connected thereto by means of an elastic material such as natural or synthetic rubber which may be vulcanized to both the cylindrical projections and the mounting blocks.

The elastic shear device 90 may be positioned with the rectangular plate 94 loosely positioned in the central recess 93 in the lower member. The mounting blocks 97 may be positioned in the recesses 98 at either end of the central recess 93, and secured in fixed relation to the lower member 92 by means of clamp blocks 99 and bolts 100.

The operation of the mounting shown in Figs. 9 through 13 is substantially the same as that described in connection with the mounting of Figs. 6, 7 and 8 with the exception that resilient movement of the elastic pivot 77, relative to the parallel motion structure, is provided by the elastic shear means 90. Accordingly, lateral deformation of the spring members 83 and 84 is substantially prevented and movement of the ends of the pantograph shoes relative to each other in a vertical direction is thus provided for.

From the above description and the accompanying drawings, it will be apparent that we have provided a current collector and a current collector mounting structure which is simple and inexpensive to manufacture, and which provides radically new operating advantages. Since movement of the pantograph shoe is limited only by the spring members themselves, frictional forces are reduced to a minimum, thus providing for relatively free operation of the pantograph and enabling it to more readily follow deviations in the trolley conductor. By providing a mounting structure using a parallel motion construction, lift of the trolley conductor is substantially prevented since there is no resultant moment from frictional drag, aerodynamic drag, and aerodynamic lift which tends to rotate the mounting structure in a direction such as to force the leading pantograph shoe against the trolley conductor.

In addition, since the effective center of rotation of the pantograph shoe is raised to a point above the surface of contact with the trolley conductor, frictional drag and aerodynamic drag no longer operate to rotate the pantograph shoe so that the leading edge is forced against the conductor with its resultant "stubbing" action. Because the reaction of the pantograph shoe to these forces in a current collector embodying our invention, is such as to cause the pantograph shoe to rotate away from the trolley conductor instead of toward it thus decreasing the angle of attack, the stability of the pantograph shoe is greatly increased. Wire friction thus tends to damp any fluttering of the shoe which may commence at the high speeds, instead of increasing the fluttering, as in the mounting structures commonly in use. By eliminating all sliding surfaces in the mounting structure, wear is reduced to a minimum, and the shoe is permitted to follow and maintain contact with the conductor more readily. The conductor stresses and wear are therefore greatly decreased due to the actions of the elastic pivot and resilient parallel support which support the pantograph shoe.

Since certain changes may be made in the above-described construction and different embodiments of the invention may be made without departing from the spirit and scope thereof, it is intended that all the matter contained in the above description and shown in the accompanying drawings shall be considered as illustrative and not in a limiting sense.

We claim as our invention:

10. A current collector comprising, a shoe having a contact surface disposed to engage a conductor, and an elastic pivot supporting the shoe comprising a closed force structure having front and back members inwardly inclined adjacent the shoe end and arranged to provide a pivot point above the contact surface of the shoe.
15. A current collector comprising, a shoe having a current collector engaging surface, and a trapezoidal elastic pivot supporting the shoe, said elastic pivot having flat springs on the front and rear so inclined towards each other as to provide a pivot point above the surface of the shoe.
20. A current collector comprising, a shoe, a support member, and a parallel motion support connecting the shoe to the support member for resilient vertical movement including relatively flat springs spaced apart in the vertical direction, said springs being connected to the support in spaced relation at one end, and maintained in fixed spaced relation to each other at the other end.
25. A current collector support comprising, a parallel motion support having relatively flat and elongated spring members connected in fixed spaced relation at spaced apart points, and an elastic pivot connected to the parallel motion support having relatively flat spring members inclined towards each other in a direction longitudinally of and away from the parallel motion support.
30. A current collector comprising, a pair of spaced support members, elongated flat spring members connected intermediate their ends to each of the support members on the tops and bottoms and extending to the front and rear thereof, means connecting the ends of the spring members on each side of the support members in fixed spatial relation, and elastic pivot structure supported by the spring members adjacent each end, and an elongated current collector shoe secured to the elastic pivot structures on the front and rear of the support members.
35. A current collector comprising, a shoe, and a closed link pivot structure supporting the shoe having rigid link members connected by elastic points, said closed link pivot structure being so constructed and arranged as to provide a center of rotation for the shoe above the contact surface with the conductor.
40. A current collector comprising, a shoe having a surface disposed to engage a conductor, and a trapezoidal elastic pivot structure supporting the shoe arranged to provide an elastic support having a pivot point above the conductor engaging surface.
45. A support for a current collector having a conductor engaging surface comprising, an elastic pivot for supporting the collector having an effective pivot point above the conductor engaging surface of the collector, and resilient parallel motion means rigidly connected to the elastic pivot.
50. A current collector comprising, a shoe having a conductor engaging surface, a parallel motion spring structure, an elastic pivot connected
55. 60. 65. 70. 75.

to the shoe providing a center of rotation above the conductor engaging surface, and means including a rubber shear bushing connecting the elastic pivot and the parallel motion spring structure to provide resilient movement of the elastic pivot transversely of the conductor.

10. A current collector comprising, a shoe, a relatively rigid parallel motion spring structure movable in a vertical direction, and an elastic pivot connecting the shoe adjacent one end of the spring structure including a pair of upwardly and inwardly inclined relatively flexible spring members.

11. A current collector comprising, a pair of spaced supports, relatively flat spring members secured to the supports on the tops and bottoms thereof in parallel spaced relation and extending to the front and rear, means connecting the front ends and rear ends of the top and bottom springs respectively, an elastic pivot having a rigid lower member connected to the lower ends of each of said means and an upper rigid member positioned above and relatively close to the top spring member and connected to the lower rigid member by flat spring members connected to the ends of the rigid members, and an elongated collector shoe rigidly connected to the upper rigid members of the front ends and the rear ends.

12. A current collector comprising, a pair of spaced supports, an elongated auxiliary shoe rigidly connected adjacent its ends to said supports, a pair of main shoes positioned one on each side of the auxiliary shoe in substantially parallel relation, and means including relatively flat spring members connecting the main shoes to the supports for vertical resilient motion, said spring being positioned apart vertically and connected to each other at spaced apart points.

13. A current collector comprising, a pair of spaced supports, a pair of main shoes positioned on opposite sides of the supports, resilient parallel motion means connecting the main shoes to the supports for resilient motion in a predetermined direction including elongated relatively flat springs positioned in spaced relation in the direction of motion and connected intermediate to their ends adjacent the tops and bottoms of the supports and also connected adjacent their ends in spaced relation to the main shoes, and an auxiliary shoe rigidly connected to the supports intermediate said pair of shoes.

14. The combination with a pantograph support structure, of a support member connected adjacent the top of each side, a pair of main shoes positioned one each on opposite sides of the supports and having conductor engaging surfaces, an elastic pivot having inwardly and upwardly inclined flat spring members at the front and rear arranged to provide for pivotal movement of the shoes about axes transverse to the conductor and above the conductor engaging surfaces, an auxiliary shoe mounted rigidly on the supports intermediate the main shoes, and means including relatively flat spring members connecting the elastic pivots to the supports on the top sides and spring members secured in fixed relation to the continuous spring members on the bottom sides of the supports.

15. A current collector comprising, a shoe having a conductor engaging surface on the upper side, and a support for the shoe comprising an

elastic pivot having a lower elongated rigid member and an upper relatively short member connected adjacent the ends by upwardly and inwardly inclined flat spring members to provide a center of rotation for the shoe above the conductor engaging surface.

16. A current collector comprising, a shoe, a trapezoidal shoe support having upper and lower links connected to inwardly inclined side links by elastic shear bushings, and a parallel motion support connected to the shoe support having upper and lower links connected in fixed spaced relation to substantially parallel end members by elastic shear bushings.

17. A current collector support comprising, an elastic pivot for supporting the collector having rigid upper and lower members connected by inclined link members, means pivotally connecting the link members to the upper member, and connecting means pivotally connecting the link members to the lower member including an elastic shear bushing connected to the lower rigid member and one of the links to provide limited movement thereof about an axis normal of the lower member.

18. In combination with a current collector disposed for resilient movement in one direction relative to a support, a parallel motion support device connecting the shoe and the support comprising a pair of relatively flat elongated spring members positioned apart in the direction of motion and secured in fixed spacial relation to each other adjacent the support and the collector.

19. The combination with a current collector disposed for resilient linear movement relative to a support, of a parallel motion device connecting the shoe and the support, said device comprising elongated spring members positioned apart in the direction of resilient movement and secured in fixed spaced relation to each other at the support and at the collector.

20. The combination with a current collector disposed to be supported for resilient movement relative to a support, of a parallel motion support device comprising a pair of elongated links spaced apart in the direction of said resilient movement, spacing means disposed adjacent the collector, and resilient connecting means including elastic shear members connecting the links to the support and spacing means in predetermined spaced relation to each other to provide limited movement about axes normal to the link members.
